UNITED STATES PATENT OFFICE.

LOUIS P. BRAULT, OF LOWELL, MASSACHUSETTS, ASSIGNOR OF ONE-HALF
TO HILAIRE DOZOIS, OF SAME PLACE.

PAPER-FOLDING MACHINE.

SPECIFICATION forming part of Letters Patent No. 323,558, dated August 4, 1885.

Application filed April 8, 1884. (No model.)

To all whom it may concern:

Be it known that I, LOUIS P. BRAULT, a subject of Victoria, Queen of the United Kingdom of Great Britain and Ireland, and residing at Lowell, in the county of Middlesex and Commonwealth of Massachusetts, have invented certain new and useful Improvements in Paper-Folding Machines, of which the following is a specification.

10 My invention relates to paper-folding machines, particularly such as are connected with newspaper printing-presses; and it has for its object to discharge from the machine any sheets which are damaged or dirty without stopping 15 the machine and before folding the paper.

In the accompanying drawings, on two sheets, Figure 1 is a side elevation of such a folding-machine with my invention applied thereto, but not in use; also, the feed-table; 20 and a part of the frame of a printing-press; Fig. 2, a side elevation of a portion of the folding-machine and my invention applied thereto with the gage raised; Fig. 3, an elevation of the other side of the folding-machine with 25 my improvement attached thereto; Fig. 4, a plan of the same.

A is the frame of a printing-press; B, the feed-table; C, the platform on which the printer stands; D, the press tape-roll; E, a sprocket-wheel, and E' a chain by which the sprocket-wheel is driven; F, a pulley on the shaft E' of the sprocket-wheel, and F' a belt connecting the pulley F to the pulley G of the upper tape-roll, G'; H, the folding-table; I I', folding-rolls, the roll I being provided with the bevel-gear i, which takes into the bevel-gear i' on the shaft E' of the sprocket-wheel E, the other feeding-roll, I', being rotated by the friction of the transverse tapes, (not shown;) J, the 30 folding-knife, by means of which and the rolls I I' the first fold is given to the sheet of paper that comes from the press. J' J' are arms, to the outer ends of which the knife J is secured, and which are themselves secured to the rock- 35 shaft J'', the latter being rocked in the usual manner. The sheets of paper, after being printed, are carried by the tapes G' and H' onto the table H beneath the knife J, which then descends, pressing the paper between the fold- 45 ing-rolls I I' in the usual manner. The tapes 50

H' are driven by the roll D, (which is revolved by the usual mechanism, not shown, as it is not a part of my invention,) and pass under the shaft E' and rest upon idle-pulleys placed thereon, as shown by the dotted circles in 55 Fig. 3.

The above-enumerated parts are well known, and are not of my invention, and therefore need no further description.

There are usually two vertical gages, or a 60 gage formed in two parts, which, standing at right angles to the path of the conducting-tapes, stop the printed sheet on the table in the proper place for the first folding operation, these gages being adjustable only toward or 65 from the shaft E' by means of a set-screw passing through a slotted shank at right angles to the gage and into the table H. The gages I use are preferably two in number, H³ H⁴, and are each provided with a shank, h h', at right 70 angles to the vertical part of the gage, and each shank runs through a collar, h² h³, secured to the rock-shaft J''. To the end of the rock-shaft J'' nearest to the printer's platform is secured a pendent arm, K³. To a bracket, K⁴, secured 75 to the side of the printing-press frame, is pivoted, at K, a bell-crank lever, K⁵, Figs. 1 and 2. The upper end of said bell-crank lever K⁵ is connected by the connecting-rod K' K² to the lower end of the arm K³, so that when the 80 lower arm of the bell-crank lever is depressed by the foot of the printer the shaft J'' is rocked, lifting the gages secured thereto and allowing the sheet, which would otherwise be stopped by the gages, to be conducted over and beyond 85 the folding-machine and onto the floor or into a suitable receptacle for waste paper.

In order that the folding-machine may be disconnected from the press in the usual manner when occasion requires, the rod is made 90 in two parts or lengths, one, K², of which is provided with a hook, k², and the other, K', with an eye, k', said hook and eye engaging with each other when the folding-machine is in use. The longer part K² of the rod is supported in and slides in a bracket, k, on the side of the frame of the folding-machine. 95

In order that the paper may be guided through the folding-machine more certainly, I provide an additional set of endless tapes, 100

H^2 , one or more tapes on each side of the knife J , which are run from the lower tape-roll, G^2 , around loose pulleys J^4 on rock-shaft J^5 . The direction in which these tapes run is shown 5 by arrows—that is, the lower half of the tapes H^2 run in the same direction with the paper—that is, to the left, in Figs. 3 and 4—so that the paper is held between two tapes traveling in the same direction.

10 In place of the upper tapes, guide-wires may be used, if properly disposed, but are not as desirable, because they do not so much assist the passage of the paper, and do not prevent its folding or creasing; and, besides, the 15 two tapes H^1 H^2 will carry out a folded or double sheet, meaning two sheets fed together.

To prevent the knife J , which is raised, as usual, by an automatic positive mechanism, but falls of its own weight between the folding-rolls I I' , from descending on the sheet 20 while the gages are raised, there is a rod, H^6 , secured to the rock-shaft J^5 , just as the shanks of the gages are secured, which rod projects over the folding-knife, and is provided with 25 an upwardly-projecting loop, H^6 . This loop is connected to the knife by a link, H^7 , which is passed through a hole in the knife J , so that when the printer rocks the shaft J^5 to raise the gages H^3 H^4 he thereby holds up the knife 30 until the paper has passed out of the machine. The loop H^6 is of such a length that the lifting of the knife in the usual manner will not rock the shaft and thereby raise the gages.

35 The proper time for the printer to operate the bell-crank lever K^5 is when he is putting the paper in the grippers, at which time the preceding sheet will be entering the first folding-rolls I I' , and he holds the gages raised until the next sheet is caught by the grippers. An average speed for a cylinder-press is about 40 twenty-five or thirty impressions a minute for each cylinder, so that there is no time for the person feeding the press to throw a damaged or dirty sheet from the pile between the revo-

lutions of the cylinder, and if the cylinder were allowed to revolve against the form of type, it would be inked and would dirty the next three or four sheets of paper. Again, if a damaged or dirty sheet is allowed to enter 50 the folding-machine, the defects in it cannot sometimes be discovered without unfolding the papers, which, in the case of a daily paper of considerable circulation, would be practically impossible. My invention enables the 55 feeder to throw out such imperfect or damaged sheets without stopping the printing-press or folding-machine and without folding the paper.

I claim as my invention—

1. In combination with the conveying-tapes of a paper-folding machine, one or more stops or gages normally arranged to arrest a sheet traveling on said tapes, the rock-shaft having an arm, said stops or gages being provided 65 with shanks secured to said rock-shaft, the bell-crank lever adapted to be operated at will, and the rod connecting said arm and lever, as and for the purpose specified.

2. The combination of the folding-table, the folding-rolls, the folding-knife, conveying-tapes, the rock-shaft, means, substantially as described, of rocking the same, the rod having 70 a loop secured thereto, and the link connecting said knife and said loop, as and for 75 the purpose specified.

3. The combination of the folding-table, the folding-rolls, the folding-knife, the conveying-tapes, the rock-shaft, means, substantially as described, of rocking the same, a rod having 80 a loop secured thereto, the link connecting said knife and said loop, and one or more gages normally arranged to arrest a sheet traveling on said tapes, as and for the purpose specified.

LOUIS P. BRAULT.
